SPINDLE BRAKE

Otto W. Schlums, Whitinsville, Mass., assignor to
Whitin Machine Works, Whitinsville, Mass., a
corporation of Massachusetts

Application March 6, 1939, Serial No. 259,952

6 Claims. (Cl. 57—88)

This invention relates to a brake for stopping the rotation of a spindle in a machine for spinning or twisting yarn.

Such spindles are commonly provided with 5 small flanged pulleys or whorls, and a plurality of associated spindles are driven by a flat cotton tape. It is frequently necessary for the operator to stop a selected spindle in order to piece a broken end or for some other purpose which 10 requires the use of both hands. It has been common to provide a knee brake for each spindle, but in modern double or 3-bank spinning or twisting frames, the upper spindles are too high and the lower spindles are too low to be conveniently knee-operated.

It is the general object of my invention to provide an improved brake which is manually controlled but which will automatically maintain braking pressure as long as the operator desires.

Another object is to provide an improved spindle brake which will apply and maintain a uniform and predetermined braking force.

A still further object is to provide a braking attachment which is a separate self-contained 25 unit, which may be conveniently applied to existing spinning or twisting frames.

My invention further relates to arrangements and combinations of parts which will be herein-after described and more particularly pointed out 30 in the appended claims.

Preferred forms of the invention are shown in the drawings, in which

Fig. 1 is a side elevation, partly in section, showing my invention mounted in a spinning or 35 twisting frame;

Fig. 2 is a plan view, partly in section, and taken along the irregular line 2—2 in Fig. 1;

Fig. 3 is a partial side elevation of a modified construction;

Fig. 4 is a view similar to Fig. 1 but showing the parts in braking position;

Fig. 5 is a rear elevation, looking in the direction of the arrow 5 in Fig. 4;

Fig. 6 is a side elevation, showing certain parts 45 in a different position; and

Fig. 7 is a detail plan view, looking in the direction of the arrow 7 in Fig. 6.

Referring to the drawings, I have shown a spindle rail 10 forming part of a spinning or 50 twisting machine and having a plurality of spindles S rotatably mounted thereon. Each spindle comprises a spindle blade 12 rotatable in a bolster 13 loosely mounted in a spindle base 14 which has a portion 15 extending downward through 55 the rail 10 and secured therein by a heavy spring

16 and clamping nut 17. The blade 12 is provided with a whorl 20 having flanges 21 and 22 and adapted to be engaged and rotated by the usual driving tape, not shown.

The parts thus far described are of the usual 5 construction and in themselves form no part of my present invention.

My improved spindle brake comprises a stand 30 which may be secured to the rear side of the spindle rail 10 by a clamping bolt 31 extending 10 through a slot 32 (Fig. 5). The stand 30 also has a projection at its upper end which provides a shoulder 33 (Fig. 1) adapted to engage the upper face of the rail 10 and thus definitely locate the stand 30 vertically.

A post 35 is fixed in the upper side of the stand 30, and a cross bar 36 is pivotally mounted at the top of the post 35 and supports a leather pad 37 in position to engage the upper face of the flange 22 of the whorl 20 if the blade and whorl 20 are slightly raised.

A keeper 38 is pivoted at 39 on the cross bar 36 and normally falls down and embraces a non-circular portion 40 of the post 35 when the arm 36 and pad 37 are in operative position. If it 25 is desired to remove the blade 12 and whorl 20 from the machine, the keeper 38 is raised and the arm 36 is swung sideways about its pivot stud 41.

A spring plate 50 (Fig. 1) is pivoted at 51 on a rearward extension 52 of the stand 30 and is 30 provided with forked ends 53 (Fig. 2) which embrace the spindle base and present leather pads 54 under the flange 22 of the whorl 20. These pads are normally spaced below the flange as shown in Fig. 1. The post 35 extends freely 35 through an opening 55 in the plate 50.

The spring plate 50 is pivotally connected by a double link 60 to an upstanding arm 61 on a bell crank lever 62. The lever 62 is pivoted at 63 to downwardly and rearwardly extending arms 64 forming part of the stand 30. The link 60 is pivoted to the spring plate at 65 and to the bell crank at 66. An arm 68 extends forward from the bell crank 62 and is provided with a handle portion 69 by which it may be conveniently 45 operated.

The lower end of the link 60 is provided with a projection 70 (Fig. 4) which engages a rear surface 71 on the bell crank 62 and forms a stop to limit downward movement of the handle arm 50 68 and spring plate 50. Upward movement of the handle arm 68 is limited by engagement of an offset portion 73 (Fig. 4) of the arm 68 by one of the depending arms 64 of the stand 30.

The parts are shown in normal or inoperative 55

- position in Fig. 1. If it is desired to stop the spindle, the operator grasps the handle 69 and swings the arm 68 upward as indicated by the arrow *a* in Fig. 1 to the position shown in Fig. 4. 5 Such movement of the bell crank 62 straightens the toggle formed by the bell crank and the link 60, thus forcing the upper link pivot 65 upward and raising the spring plate so that the pads 54 will engage the under side of the flange 22 and 10 force the spindle blade and whorl upward against the fixed pad 37.

Further movement of the bell crank 68 places the spring plate under tension as indicated in an exaggerated manner in Fig. 4 and carries the 15 pivot 66 beyond the center line joining the pivots 63 and 65. At this point, further movement of the bell crank is stopped by engagement of the offset shoulder 73 and the arm 64, and the parts will remain indefinitely in this position, with the 20 spring plate 50 under tension.

The operator is thus free to use both hands for piecing a broken end or for other purposes and the spindle will be held from rotation as long as desired. The operator then returns the 25 arm 68 to normal lowered position and the spindle is thereby rendered free to rotate.

It will be noted that the entire braking device forms a self-contained and separate unit, which may be attached to an existing spinning or twisting 30 frame by the single clamping bolt 31.

In the modification shown in Fig. 3, the post 35 is omitted and the fixed pad 80 is mounted on an arm 81, pivotally secured by a stud 82 at the top of the oiling projection 83 formed at the 35 edge of the spindle base 84. The operation is identical with the construction previously described, but differs therefrom in providing the fixed pad 80 as a part of the spindle structure, rather than as a part of a self-contained braking 40 unit.

It should be particularly noted that the upward pressure of the pads 54 is determined by the stiffness of the spring plate 50, the length of the link 60, and the relative location of the pivots 63, 45 65 and 66. Consequently the pressure will be uniform every time the brake is applied and does not in any way depend upon the operator, who merely shifts the handle 69 upward and downward between its fixed limits to apply and release the brake.

Having thus described my invention and the advantages thereof, I do not wish to be limited to the details herein disclosed, otherwise than as set forth in the claims, but what I claim is:

- 55 1. In a spinning or twisting machine having a spindle rail and a plurality of spindles mounted thereon and each provided with a flanged driving whorl, that improvement which comprises a brake for each spindle having friction elements 60 engaging the top and bottom faces of a whorl flange, manually-operated means to relatively move said elements to apply friction pressure to said flange, and means to automatically determine the amount of friction pressure applied on 65 said flange and to automatically and independently maintain said pressure for an indefinite period after manual application thereof.

2. In a spinning or twisting machine having

a spindle rail and a plurality of spindles mounted thereon and each provided with a flanged driving whorl, that improvement which comprises a brake for each spindle having friction elements 5 engaging the top and bottom faces of a whorl flange, a spring plate on which certain of said friction elements are mounted, manually operated means to put said spring plate under tension to apply friction pressure to said whorl flange, and means to automatically limit said pressure and to automatically maintain said limited pressure for an indefinite period after manual application thereof.

3. In a spinning or twisting machine having a 15 spindle rail and a plurality of spindles mounted thereon and each provided with a flanged driving whorl, that improvement which comprises a brake for each spindle having friction elements engaging the top and bottom faces of a whorl flange, a spring plate on which certain of said friction 20 elements are mounted, manually-operated toggle means to put said spring plate under tension to apply friction pressure to said whorl flange, and means to thereafter automatically maintain said toggle in holding position.

4. In a spinning or twisting machine having a spindle rail and a plurality of spindles mounted thereon and each provided with a flanged driving whorl, that improvement which comprises a brake for each spindle having friction elements 30 engaging the top and bottom faces of a whorl flange, a spring plate on which certain of said friction elements are mounted, a manually operated lever, a link connecting said spring plate and lever and forming a toggle with said lever, and a stand fixed to said rail and on which said 35 plate and lever are pivotally mounted.

5. In a spinning or twisting machine having a spindle rail and a plurality of spindles mounted thereon and each provided with a flanged driving 40 whorl, that improvement which comprises a brake for each spindle having friction elements engaging the top and bottom faces of a whorl flange, a spring plate on which certain of said friction 45 elements are mounted, a manually operated lever having a shoulder thereon, a link connecting said spring plate and lever, a stand to pivotally support said plate and lever, and a projection on said link engageable with said shoulder on said lever to determine the inoperative position 50 of the parts.

6. In a spinning or twisting machine having a spindle rail and a plurality of spindles mounted thereon and each provided with a flanged driving whorl, that improvement which comprises a 55 brake for each spindle having friction elements engaging the top and bottom faces of a whorl flange, a spring plate on which certain of said friction elements are mounted, a manually operated lever having a shoulder thereon, a link 60 connecting said spring plate and lever, a stand to pivotally support said plate and lever, a projection on said link engageable with said shoulder on said lever to determine the inoperative position of the parts, and a portion of said lever 65 engaging a part of said stand to determine the holding position of said parts.

OTTO W. SCHLUMS.
